UNITED STATES PATENT OFFICE.

ROSE W. SMITH, OF LEXINGTON, MASSACHUSETTS.

ORNAMENTAL PLAQUE.

1,143,601.

Specification of Letters Patent. Patented June 15, 1915.

Application filed December 4, 1914. Serial No. 875,523.

To all whom it may concern:

Be it known that I, ROSE W. SMITH, a citizen of the United States, and a resident of Lexington, in the county of Middlesex and Commonwealth of Massachusetts, have invented an Improvement in Ornamental Plaques, of which the following description, in connection with the accompanying drawings, is a specification, like characters on the drawings representing like parts.

This invention aims to provide a novel, ornamental plaque that may be used for ornamental purposes only or, and preferably, as in the shape of a useful tray or other article.

Prior to my invention it has been common to provide plaques of this nature by superposing two plates of glass, of desired size and shape, with interposed butterflies, for example, and various grasses and flowers, with a backing of milkweed scattered throughout the area of the plaque, the whole being pressed together by the glass plates at opposite sides, and suitably framed or arranged in a rim or carrier according to the particular use for which it is desired.

The milkweed as a background is quite transparent, the same presenting an appearance somewhat like frosted glass when presented to the light, the ornamental or decorative elements resting upon this background but, because heavier or more substantial than the milkweed, pressing the latter back to a level below that of the decorative elements.

To improve the decorative effect of plaques or panels of this character my invention comprehends a novel background, composed of closely arranged, substantially parallel fibers, that form a substantially translucent background for the decorative elements and, by reason of close contact with the glass plates at either side, cause the decorative elements to be appreciably embedded therein, to produce a shaded or deepening effect that tends to bring out the decorative features and add to the strength and beauty of the plaque as a whole. This will best be understood by reference to the accompanying drawing, illustrating one embodiment of this invention, in which—

Figure 1 represents in face view a decorative panel, framed to stand on a mantel or other convenient support, Fig. 2, a cross section on the dotted line, Fig. 1, and Fig. 3, an enlarged detail, illustrating the shadow-

producing depression of the decorative elements in the fibrous backing.

Referring to the drawings, particularly to Figs. 1 and 2, the two plates of glass or other suitable material of desired transparency or translucency are indicated at 3, 4, and the space between them is filled and practically determined by a background filling 5 (Fig. 3) of closely arranged, substantially parallel fibers. These may be combed wool or cotton, the latter either natural or mercerized, or, and preferably, may be what is known in the art as "spun silk tops." The latter present a silky appearance, the fibers of which are substantially parallel though more or less wavy, and when used to substantial thickness, as in the drawings, present a practically translucent background but with all the variegated effects due to the wavy lines and differences in density. The effect, except as to color, very much resembles what is known as deep agate glass. It is of course, to be understood that these fibers are in an unwoven condition. Overlying that face of the backing which is next the under side of the top glass are the ornamental or decorative elements, herein shown as butterflies 6 and branches or members 7, 8, of delicate or dainty grasses and flowers or the like. By pressing the two glass plates together with the translucent, fibrous backing and the superposed decorative elements between them, the fibrous backing is caused substantially to fill the space between the plates of glass, lying in full and fair contact with the inner face of each glass plate, with the decorative elements depressed or embedded therein at the face next the top glass, whereby the decorative elements are strengthened and brought into greater relief and prominence by the shading due to the depressions they themselves make in the fibrous backing. When viewing the plaque, the backing lying close against the top glass throughout substantially the entire area of the plaque, produces an effect that can not be had by any form of backing that does not completely fill the space between the glass plates. Each member of the decorative elements, however minute it may be, while it is lying close against the top glass and thereby in position to produce its highest effect, produces a corresponding depression in the fibrous backing lying immediately adjacent thereto (as best shown in Fig. 3), and following its outline, the depression by the

more minute decorative elements being, of course, proportionately less than that produced by the heavier and stronger elements.

In the decorative panel or plaque herein disclosed there is a translucent layer of spun-silk top fibers substantially parallel throughout but having in mass separated areas presenting a marked wavy appearance, said fibers being in lateral contact and the layer being of such depth and character as to exclude light in a marked degree when presented thereto, said layer being in close contact with the underside of said transparent face, and the said fibers partially and readily reflecting light, but with a softened, broken effect of blended light and shade from the different portions of the surface of the layer.

The effect of the whole is to produce a highly satisfactory result, wherein lightness and daintiness of decorative effect is combined with an apparent firmness and strength that can only go with a translucent, fibrous backing of the character described.

In use the glass plates, with the between decorations, are suitably mounted in a frame 9, which may be purely ornamental, as for an ornamental plaque, or, if desired, formed in the shape of a rim, with or without handles, for some useful purpose.

I claim—

1. In a decorative panel having a transparent face, a translucent layer of substantially parallel fibers, in close lateral relation to prevent the free passage of light, and of such depth and character as to exclude light in a marked degree when presented thereto,

said layer being in close contact with the underside of said transparent face, and the fibers thereof partially and readily reflecting light, but with a softened, broken effect of blended light and shade, and superposed, decorative elements overlying said translucent layer, and depressed therein by the overlying transparent face, thereby to cause shade-producing depressions following the outlines of said decorative elements.

2. In a decorative panel having a transparent face, a translucent layer of spun silk top fibers substantially parallel throughout but having in mass separated areas presenting a marked wavy appearance, said fibers being in close lateral relation to prevent the free passage of light, and the layer being of such depth and character as to exclude light in a marked degree when presented thereto, said layer being in close contact with the underside of said transparent face, and the said fibers partially reflecting light, but with a softened, broken effect of blended light and shade from the different portions of the surface of the layer, and superposed, decorative elements overlying said translucent layer and depressed therein by the overlying transparent face, thereby to cause shade-producing depressions following the outlines of said decorative elements.

In testimony whereof, I have signed my name to this specification, in the presence of two subscribing witnesses.

ROSE W. SMITH.
